UNITED STATES PATENT OFFICE.

FRANK H. HOWARD, OF READING, PENNSYLVANIA.

DESIGN FOR A CHAIN-WELDING-MACHINE FRAME.

51,282.

Specification for Design.

Patented Sept. 18, 1917.

Application filed July 5, 1917. Serial No. 178,875. Term of patent 7 years.

To all whom it may concern:

Be it known that I, FRANK H. HOWARD, a citizen of the United States of America, residing in the city of Reading, county of Berks, State of Pennsylvania, have invented a new, original, and ornamental Design for a Chain-Welding-Machine Frame, of which the following is a specification, reference being had to the accompanying drawing forming a part thereof.

In the drawing:

Figure 1 is a front elevational view of my new design, and,

Fig. 2 is a side elevational view thereof.

I claim:

The ornamental design for a chain welding machine frame, as shown.

FRANK H. HOWARD.
